UNITED STATES PATENT OFFICE.

ORMOND F. CASSADAY, OF CHICAGO, ILLINOIS, ASSIGNOR TO KELLOGG SWITCHBOARD AND SUPPLY COMPANY, OF CHICAGO, ILLINOIS, A CORPORATION OF ILLINOIS.

COMPOSITE RINGER CIRCUITS.

Application filed May 21, 1919. Serial No. 298,765.

To all whom it may concern:

Be it known that I, ORMOND F. CASSADAY, a citizen of the United States of America, residing in Chicago, county of Cook, and **5** State of Illinois, have invented certain new and useful Improvements in Composite Ringer Circuits, of which the following is a specification.

My invention relates to signaling systems **10** in general and has to do most particularly with the so-called composite ringing circuits as are used in conjunction with composite telephone and telegraph circuits.

Composite telephone and telegraph circuits as now in use have deficiencies in that, when signaling current is applied to signal a distant station it interrupts and interferes with the regular telegraph signals and the thumps or discharges from the telegraph circuits when in use will cause false signals to be transmitted.

An object of my invention is to produce a system of the above character which overcomes the above objections and which is **25** simple in construction, most efficient in its operation and accomplishes signaling without the objections found in prior systems.

A feature of my invention is the provision of a relay of the vibrating type which is **30** only responsive to signaling current of a high frequency and is non-responsive to the ordinary telegraphic discharges of the telegraph circuit.

Another feature of my invention is the **35** provision of a circuit arrangement of telephonic devices in association with telegraphic devices and including my vibrating relay in association with other apparatus thereby providing an improved means for **40** signaling a distant station and eliminating the liabilities of false signaling due to telegraphic discharges, as well as interfering with the telegraphic devices when a distant station is signaled.

45 The novel features of the invention through the provision of which the above-mentioned and other advantageous results are attained, will be explained by reference to the accompanying drawings, in which like reference characters in the several views denote like parts, and in which

Fig. 1 is a front view of the relay of my invention with the protective cap in section;

55 Fig. 2 is a left side elevation of Fig. 1;

Fig. 3 is a sectional view of the relay taken along the line 3-3 of Fig. 1;

Fig. 4 is a sectional view along the line 4-4 of Fig. 1;

Fig. 5, which comprises parts 1, 2 and **60** 3, illustrates diagrammatically a circuit arrangement embodying the features of my invention.

Referring now more in detail to my invention as illustrated and more particularly **65** to the relay structure as illustrated in Figs. 1 to 4, inclusive, the relay of my invention comprises a U-shaped permanent magnet 2 to which is secured a soft yoke member 3 which is secured to the leg 4 of the permanent magnet 2 by means of a stud 5. The stud 5 passes through suitable openings in the leg 4 of the magnet 2 and the yoke 3, and the end which passes through the said openings is up set, as clearly illustrated **70** in Fig. 3, to secure the yoke 3 to the magnet 2. A pair of electromagnet coils 6 and 7 are secured to legs 8 and 9 of the yoke member 3 by means of the screws 10, which screws 10 have screw-threaded engagement **75** with suitable tapped openings in the cores 11 of the electromagnets 6 and 7. A mounting plate 12 of suitable insulation material such as bakelite or micarta is secured to the leg 13 of the permanent magnet 2, by means of a stud 14, which stud 14 is provided with a threaded portion 15, that passes through suitable openings in the plate 12 and leg 13.

A nut 16 is provided and has screw-threaded engagement with the threaded portion 15 of the stud 14, so that when the nut 16 is screwed down, it clamps the said mounting plate 12 to the permanent magnet 2. An L-shaped reed armature 17 is provided and is secured to the stud 14 in any suitable **80** manner, preferably by cutting a slot 18 in the stud 14 of a size to receive the reed armature 17, and the armature when thus placed may be soldered or anchored to the stud 14. The free end of the armature 17 extends downward and rests between the cores 11 of the electromagnets 6 and 7, and is acted upon by the said electromagnets **85** 6 and 7.

A resilient spring member 20 is provided **90** and is secured to the mounting plate 12 in any suitable manner as by means of the rivet 21. An angular extension 22 of the spring member 20 extends through a suitable opening in the mounting plate 12 and serves **95** 110

as a terminal for the said spring member 20. The free end of the spring is provided with a weight 23 secured to the free extremity of the spring in any suitable manner, for purposes as will be more fully hereinafter described. The reed armature 17 is provided with an arm 24 with which the resilient spring member 20 is normally in engagement. The arm 24 acts upon the spring 20 when the reed armature is vibrated. Terminals 25 and 26 are suitably secured to the mounting plate 12 by means of rivets 27 and the terminal ends 25' and 26' serve as terminals for the windings of the coils 6 and 7, and the terminal ends 25² and 26², which are angularly disposed, extend through suitable openings in the mounting plate 12 and serve as terminals for external connections. Brackets 28 and 29 are provided and are secured to the mounting plate 12 by means of the rivets 30 and serve as a mounting means for the relay. A protective cap or cover 31 is provided and is slipped over the relay structure and held in place by means of a thumb nut 32, which nut has screw-threaded engagement with the threaded portion 33 of the stud 5.

When current passes through the coils 6 and 7, the reed armature 17 is acted upon, causing the said reed armature 17 and spring 20 to be vibrated. By reason of the L-shaped construction of the reed armature 17, it vibrates with a node at the point where the armature 17 impinges the cores of the electromagnets 6 and 7 and the vibrations of the angular portion 24 of the armature 17 at its end are the reverse of the vibrations between the node and the supporting stud 14. The rate of vibration of the spring 20 is much lower than that of the reed armature 17, partly because it is lighter than the reed armature, and partly because its weight is unequally distributed, due to the mass or weight 23 at its free end. The reed armature 17 and the spring 20 possess diverse motions and therefore, when the reed armature 17 and the spring 20 are vibrated, the armature 17 and spring 20 pull away from each other. The spring 20, due to its construction, can not follow promptly the vibrations of the reed armature 17, so that the contact between the said armature 17 and spring 20 is broken at this time. The length of the spring 20 and reed armature 17 and weight 23 is so balanced that varying adjustments can be given to this relay to meet the conditions of different circuit conditions, and the construction permits of a wider range of adjustment because of it being non-responsive to telegraphic impulses and responsive only to high frequency current impulses.

Having described the relay of my invention, I will now describe in general the ap-

paratus as illustrated in Fig. 5, parts 1, 2 and 3, which shows a composite telephone and telegraph circuit embodying the features of my invention. Referring now to Fig. 5, part 1, at the left hand side I show a local battery substation of a well-known type, and comprising the usual substation equipment. The local battery substation A terminates at the exchange in a line circuit L, including the usual combined drop signal DS and jack J. The cord circuit B comprises the usual answering plug AP and calling plug CP, a listening key LK which key when actuated connects the operator's set O to the cord conductors. A ringing key RK is also shown, which key, when actuated, connects the ringing generator G to the plug CP for signaling purposes, and a clearing out signal or drop CL is provided for the usual supervisory purposes. A composite ringing circuit C for signaling a distant station terminates at one end in a trunk jack TJ and associated therewith is a drop signal DS'. A ringing relay RE is provided, which is normally energized and when de-energized connects ringing generator G' for signaling purposes. A repeating coil RC is associated with an alternating current relay AC. A high frequency interrupter I is provided and comprises an interrupter relay IR, a retard coil RD and an induction coil IC in association with a switching relay SW. Relay SW when actuated associates generator G² with the interrupter I, for purposes as will be more fully hereinafter described. The high frequency relay HF is also provided, which is preferably constructed as shown in Figs. 1 to 4, inclusive.

Referring now to Fig. 5, part 2, I here illustrate composite circuits D and D', which comprise the usual retardation coils RA, RA' and RA² and RA³, respectively. Morse or telegraph sets TS and TS' are operatively associated with the circuit D and located at a terminal point and sets TS² and TS³ are operatively associated with the circuit D' and located at a terminal point, as is well understood. The sets TS, TS', etc. comprise the usual Morse relay MR, key K and relay M for the usual sending and receiving purposes, as is well understood.

In Fig. 5, part 3, I illustrate a composite ringer circuit E which is similar to the circuit illustrated in Fig. 5, part 1, and comprises an interrupter I', which includes retardation coil RD', an induction coil IC', an interrupter relay IR', and ringing generator G³. I also provide an alternating current relay AC', a high frequency relay HF', repeating coil RC', a ringing relay RE' and its associated ringing generator G⁴. The circuit E at its right end terminates in a trunk jack TJ' and usual drop signal DS². The cord circuit C' for inter-

connecting purposes comprises the usual answering and calling plugs AP' and CP', ringing and listening keys RK' and LK' for connecting respectively the ringing generator G³ and operator's set O' to the cord conductors when actuated, and a clearing out drop signal CL' for the usual purposes. I also show a called local battery substation F which terminates at the exchange in the usual drop signal DS³ and jack J'.

The lines L and L' may be trunk or toll lines, and are shown as subscribers' lines for illustration purposes only.

Having described in general the apparatus embodying the preferred form of my invention, I will now describe in detail the operation of the circuit as illustrated. Assuming now that the subscriber at the substation A initiates a call, the actuation of the hand generator thereat actuates the drop signal DS at the exchange and the operator noting the actuated drop signal DS inserts the answering plug AP of the cord circuit C into the jack J of the line, which insertion restores the drop signal DS. The operator now actuates her listening key LK to connect her operator's set O to the cord conductors and inquires the wants of the calling subscriber at substation A. Assuming further that it is the substation F at the distant exchange that is wanted, the operator inserts the calling plug CP into the trunk jack TJ and actuates the ringing key RK to connect the generator G with the trunk jack. The ringing current then flows from the ungrounded pole of the generator G, through the tip contacts of the connected plug CP and trunk jack TJ, alternate contact 2 of the ringing relay RE, windings 3, 4, 5 and 6 of the repeating coil RC, conductor 7, condenser 8, through the winding of the alternating current relay AC, conductor 9, alternate contact 10 of relay RE, and the sleeve contacts of the connected plug CP and jack TJ to ground. The circuit of relay RE, which is normally energized, extends from battery through the winding of relay RE, and over conductor 11, to ground at normal contact 12 of high frequency relay HF. The alternating current relay AC, upon actuation, closes its alternate contact 13, closing an energizing circuit for the switching relay SW, traced from battery, through the winding of relay SW and over conductor 14 to ground at alternate contact 13 of relay AC. Ringing current from generator G also passes through the high frequency relay HF, but as switching relay SW is energized as soon as relay AC actuates, the circuit for relay HF is opened at normal contact 15 of relay SW and should the normal contact 12 of relay HF open, the ringing relay RE being a slow-acting relay, is held energized due to its slow to release action, thus preventing a false signal being sent.

The switching relay SW upon energization closes its alternate contacts 16, 17 and 18 and the closing of alternate contact 17 connects ringing generator G² with the interrupter circuit I, the circuit being traced 70 from the generator G², over conductor 19, through alternate contact 17 of relay SW, conductor 20, normal contact 21 of relay RI, through the winding of the interrupter relay IR, conductor 22, the winding 23 of the induction coil IC, conductor 24, to the other pole of the generator G². This interrupted current is induced into the winding 25 of the induction coil IC and this high frequency current extends from the winding 25 of the 80 induction coil IC, through winding 26 of the retardation coil RD, conductor 27, alternate contact 16 of switching relay SW, over conductor 28, through normal contact 29 of switching relay SW', conductor 30, windings 31, 32, 33 and 34 of the repeating coil RC, conductor 35, condenser, 36, windings 37 and 38 of the high frequency relay HF', conductor 39, normal contact 40 of switching relay SW', conductor 41, normal contact 42 of relay SW', conductor 43, alternate contact 18 of relay SW, conductor 44, through the winding 45 of retardation coil RD to the other side of the winding 25 of the induction coil IC. The high frequency 90 current does not affect the drop signal DS² or the alternating current relay AC', but the high frequency relay HF' is responsive to the current which passes through its windings 37 and 38 and causes the reed armature to vibrate to open the normally closed contact between the said reed armature and the resilient spring member, as previously described, and the opening of normally closed contact 46 of relay HF', due to its vibration, 100 opens the energizing circuit for ringing relay RE' (which relay RE' is normally energized when relay HF' is at normal) permitting the same to de-energize. The relay RE' upon de-energization closes its normal 110 contacts 48 and 49 which connects current from the ringing generator G⁴ through normal contact 48 of relay RE', normal contact 50 of trunk jack TJ', the winding of drop signal DS², and normal contact 51 of 115 trunk jack TJ' to ground at normal contact 49 of relay RE'. Current passing through the winding of the signal DS² actuates it.

The operator at the exchange, at which called substation F terminates, noting the actuated drop signal DS³, inserts an answering plug AP' into the trunk jack TJ' of the actuated drop and operates her listening key LK to connect her set O' across the conductors of the cord C'. She now inquires the wants of the calling subscriber and receiving the information that it is the subscriber at substation F that is wanted, inserts the calling plug CP' into the jack J' 130

of the called line and actuates her ringing key RK' . The actuation of the ringing key RK' connects ringing generator G^5 to the call signal at the called substation F , and the subscriber in response to the signal, removes his receiver from his switch hook. The subscriber at the calling substation A and the subscriber at the called substation F are now in conversational circuit, which 10 may be traced over the heavily marked conductors.

Assuming now that the subscribers at the calling and called substations A and F have finished conversation, the subscriber at the substation A replaces his receiver and actuates his hand generator, causing current to flow through the clearing out drop CL of the cord circuit C , thereby actuating the same. The operator seeing the actuated 20 drop knows that the subscriber at substation A has replaced his receiver and withdraws the answering and calling plugs AP and CP from the jacks J and TJ . The subscriber at the called substation F replaces his receiver and actuates his hand generator to operate drop CL' of cord circuit C' . The operator then withdraws the answering and calling plugs AP' and CP' from the jacks TJ' and J' . The apparatus used in establishing the connection described is now at 25 normal and available for establishing other connections.

Assuming now that the subscriber at the substation F is a calling subscriber, the actuation of his hand generator at the substation causes the drop signal DS^3 to operate and the operator noting the signal, inserts the answering plug AP' in the jack J' and actuates her listening key LK' to 30 connect her set O' across the calling line, and inquires the wants of the calling subscriber. It being the subscriber at substation A that is wanted, she inserts the calling plug CP' into the jack TJ and actuates the ringing key RK' , thereby connecting generator current from generator G^5 to trunk jack TJ' to actuate the alternating current relay AC' , as is readily understood from the 35 previous description. The relay AC' upon energization closes its alternate contact 70, closing an energizing circuit for the switching relay SW' , traced from battery, through the winding of relay SW' to ground at alternate contact 70. Relay SW' upon energization 40 closes its alternate contacts 29, 42 and 71. The closing of contact 71 connects generator G^3 to the interrupter circuit I' , causing high frequency current to be delivered from the interrupter circuit I' through alternate contact 29, over conductor 28, normal contact 16 of relay SW , windings 3, 4, 5 and 6 of repeating coil RC , windings 72 and 73 of high frequency relay HF , normal contacts 15 and 18 of relay SW , conductor 43 to alternate contact 42 of relay SW' . The

high frequency current generated by the devices I or I' is of such a character that it does not affect any of the telegraphic instruments. The high frequency current actuates relay HF , which opens its normal contact 12 to allow relay RE to restore, and relay RE restoring, closes its normal contacts 2 and 10, connecting generator G' to the drop signal DS' to bring about its actuation. The operator at the distant exchange 70 noting the signal, inserts her answering plug AP into the jack TJ and finding that it is substation A that is wanted, inserts the calling plug CP into the jack J and signals in 75 the usual manner, and in response to the signal the subscriber at A answers and conversation may now be carried on. Disconnection is the same as previously described and a further description is not deemed necessary. 80

The telegraphic instruments may be used while telephonic connections are being carried on over the trunk circuit without in any way affecting the telephonic conversation or the telephone apparatus. 85

Assuming that it is desired to operate the telegraphic set TS to send a message to telegraphic station TS^2 , the opening of contact 150 of the said key K opens the circuit of relay M . The relay M is normally held energized over a circuit traced from the positive pole of the battery, through the winding of relay M , normal contact 150 of the key K , conductor 151, windings 52 and 53 of the retardation coil RA' , conductor 28, windings 54 and 55 of the retardation coil RA^2 , normal contact 56 of key K^3 , and through the winding of relay M^3 to the other pole of battery and to ground. The operation of key K for signaling purposes thus actuates the relays M and M^3 causing Morse relays MR and MR^3 to energize and de-energize for signaling purposes, as is well understood. When the key K' of the telegraph set TS' is actuated, the relay M^2 at 100 station TS^2 is actuated. Likewise, when keys K' and K^3 are operated, relays M' and M at stations TS' and TS , respectively, are actuated. The thump or discharges from the telegraph circuits which may pass out over the line, do not affect the high frequency relays HF or HF' , due to their construction, so that no false operations of relays RE or RE' are brought about to cause the transmission of false impulses. The retardation coils RA , RA' , RA^2 and RA^3 are for the usual purposes, as is well understood in the art of composite circuit construction, whereby telegraph and telephone circuits 115 may operate simultaneously over the same circuit. 120

While I have illustrated and described a preferred embodiment of my invention, I do not wish to be limited to the same as my invention is applicable with other circuit ar- 125

rangements. Changes and modifications will also readily suggest themselves to those skilled in the art, and I, therefore, aim to cover all such changes and modifications as come within the spirit and scope of the appended claims.

Having described my invention what I claim as new and desire to secure by United States Letters Patent is:

- 10 1. A system of the character described including a trunk circuit terminating in a pair of terminals, a high frequency generator for connection to said trunk circuit, a high frequency relay and an alternating current relay in multiple circuit for each end of said trunk circuit, a normally energized relay for each end of said trunk circuit, a central office signal associated with one of said terminals, and generator means for operating said central office signal, generator means for operating the said alternating current relay associated with the said one of said terminals, a pair of switching relays for said trunk circuit, means including said alternating current relay and one of said switching relays for connecting said high frequency generator to said trunk circuit to operate the high frequency relay at the other end of said trunk circuit to effect the normally energized relay of said other end of said trunk circuit to connect said first generator to said trunk circuit to operate the said central office signal to notify the operator that a call is being extended over said trunk circuit.
- 20 2. A system of the character described including a trunk circuit terminating in a pair of terminals, a high frequency generator connected in circuit with said trunk circuit, a high frequency relay and an alternating current relay in multiple circuit at each end of said trunk circuit, said relays being connected in circuit with said trunk circuit, a normally energized relay at each end of said trunk circuit, a central office call signal connected to one of said terminals, means controlled by said normally energized relay of said one terminal for operating said call signal, a low frequency generator associated with the other of said terminals, means for applying current from said last generator to said trunk circuit, a pair of switching relays for said trunk circuit, means including one of said alternating current relays and one of said switching relays controlled by said application of current for connecting said high frequency generator to said trunk circuit to operate the high frequency relay at the other end to effect said energized relay of said one terminal to connect said first means in circuit with said call signal whereby said call signal is caused to operate, telegraphic instruments connected to each conductor of said trunk circuit, and means for so connecting said instruments that they
- 25 3. A system of the character described including a two conductor trunk circuit provided with a pair of terminals, switching relays for each end of said trunk circuit, an individual alternating current relay, a high frequency relay and a normally energized relay for each end of said trunk circuit, the alternating current relay and the high frequency relay at each end of said trunk circuit being in multiple circuit with each other, high frequency generating means for connection to said trunk circuit by one of said switching relays, a central office call signal connected to one of said terminals and a generator adapted to be connected by one of said switching relays with said one terminal to operate said call signal, ringing current means, means for connecting said ringing current means to the other end of said trunk, means including one of said alternating current relays and one of said switching relays responsive to said ringing current for connecting said high frequency generating means to said trunk circuit to operate one of said high frequency relays and one of said switching relays at said first terminal to effect said energized relay of said first terminal to connect said first generator to said one terminal to effect operation of said call signal to notify the central operator that it is desired to extend a call over said trunk circuit.
- 30 4. A system of the character described including a trunk circuit provided with a pair of terminals, high frequency generating means for connection to said trunk circuit, a signal connected to one of said terminals, a generator for operating said signal, a normally energized relay for maintaining said generator out of circuit with said signal and said terminals, ringing current means, means for applying ringing current from said ringing current means to the other of said terminals, means including an alternating current relay and a switching relay responsive to said current for connecting said high frequency generating means to said trunk circuit, means controlled by said normally energized relay for connecting said first generator to said terminal and said signal, a high frequency relay connected with said terminal responsive to current from said high frequency generating means for de-energizing said normally energized relay to connect said first generator to said first terminal and said signal for operating the same, telegraphic instruments connected to each conductor of said trunk circuit, and means for so connecting said instruments that they are unaffected by the current from said generators.
- 35 5. A system of the character described including a two-way trunk circuit provided

with terminals, telegraphic instruments connected to each of the conductors of said trunk circuit whereby telegraphic messages may be sent each way over each of said 5 trunk conductors, a central office call signal connected to each of said terminals, generators for operating said signals, a high frequency generating device, a high frequency relay and an alternating current relay and 10 a switching relay and a normally energized relay operatively connected with each of said terminals, means for applying ringing current to either of said terminals to operate the alternating current relay and the switching 15 relay at the same terminal to which said ringing current is applied to connect the associated high frequency generating device with the trunk circuit to operate the high frequency relay at the opposite end of said 20 trunk circuit to effect said normally energized relay at the opposite end of said trunk circuit for connecting the generator at that end with its associated signal to operate its associated signal thereby apprising 25 the central office operator of a call.

6. A system of the character described including a two-way trunk circuit provided with terminals, telegraphic instruments connected to each of the conductors of said trunk circuit whereby telegraphic messages may be sent each way over each of said trunk conductors, a signal connected to each of said terminals, an individual generator for each of said signals for operating said signal's, a normally energized relay for each terminal for normally maintaining said generator out of circuit with its associated terminal and signal, a high frequency generating device and a high frequency relay connected with each of said terminals, means controlled by said high frequency relay for controlling said normally energized relay, switching means, means for applying ringing current to either of said terminals for operating said switching means to connect the associated high frequency generating device with the trunk circuit to operate the high frequency relay at the opposite end of said trunk circuit to operate the said first means to cause said normally energized relay to de-energize thereby connecting the generator at that end with its associated terminal and signal to operate said signal, and telephonic mechanism for holding conversations over said trunk circuit, said telephonic mechanism, signaling mechanism and telegraphic mechanism being so connected as not to interfere with the operation of each other.

7. A system of the character described including a two-way trunk circuit provided with terminals, telegraphic instruments connected to each of the conductors of said trunk circuits whereby telegraphic messages may be sent each way over each of said

trunk conductors, a signal connected to each of said terminals, an individual generator for each of said signals for operating its associated signal, said generator normally disconnected from its associated signal and terminal by a normally energized relay, a high frequency generating device and a high frequency relay connected with each of said terminals, said normally energized relay being controlled by one of said high frequency relays, switching means, means for applying ringing current to either of said terminals to actuate said switching means to connect the associated high frequency generating device with the trunk circuit to operate the high frequency relay at the opposite end of said trunk circuit to cause said normally energized relay to de-energize thereby connecting the generator at that end with its associated terminal and signal to operate said signal, said high frequency relays being so constructed and connected as to be unaffected by the telegraphic impulses when the telegraphic instruments are in use.

8. A system of the character described including a two-way trunk circuit terminating at its opposite ends in jacks, a telephone line, a link circuit connected to said telephone line and to said trunk circuit via one of said jacks, a central office signal connected with the other jack of said trunk circuit, a switching relay operatively associated with an alternating current relay connected to one end of said trunk circuit to which said link circuit is connected, a generator for said trunk circuit for actuating said signal, a high frequency relay connected to the other end of said trunk, a high frequency generator, a second switching relay, a generator operatively associated with the said link circuit for applying generator current to said trunk circuit to operate said A. C. relay whereby said first switching relay is actuated to connect said high frequency generator to said trunk circuit, thereby causing the actuation of said high frequency relay, which relay causes the actuation of said second switching relay to connect said first generator to said trunk circuit to effect the actuation of said central office signal to notify the operator at the distant end of the trunk circuit that a connection is desired, a called subscriber's line, and a second link circuit connecting said trunk circuit to said called line.

9. A system of the character described including a two-way trunk circuit terminating at its opposite ends in jacks, a telephone line, a link circuit connected to said telephone line and to said trunk circuit via one of said jacks, a central office signal connected with the other jack of said trunk circuit, a switching relay operatively associated with an alternating current relay connected to one end of said trunk circuit

to which said link circuit is connected, a second switching relay, a generator for said trunk circuit for operating said signal, a high frequency relay connected to the other 5 end of said trunk, a high frequency generator, another generator adapted to be connected with the said link circuit for applying generator current to said trunk circuit to operate said A. C. relay whereby said 10 first switching relay is actuated to connect said high frequency generator to said trunk circuit, thereby causing the actuation of said high frequency relay, which relay causes the actuation of said second switching relay to 15 connect said first generator to said first trunk circuit to cause the actuation of said central office signal to notify the operator at the distant end of the trunk circuit that a connection is desired, a called subscriber's 20 line, a second link circuit connecting said trunk circuit to said called line, and telegraphic instruments connected to each conductor on the said trunk circuit, said telegraphic and telephonic instrumentalities being 25 so connected as not to interfere with the correct operation of each other.

10. A system of the character described including a calling subscriber's line and a called subscriber's line, a trunk circuit terminating at its ends in two different exchanges, a link circuit for connecting said calling subscriber's line to one end of said trunk circuit at one exchange; a central office signal connected to the other end of said 30 trunk circuit at the other exchange, means for said trunk circuit for actuating said signal, a high frequency relay, a high frequency generator, and a switching relay operatively associated with each end of said trunk circuit; the high frequency generator at one end of said trunk circuit adapted to operate the high frequency relay at the other end of said trunk circuit via 35 said trunk circuit, and the switching relay at said one end adapted to connect the high frequency generator to the trunk circuit, ringing current means, a second switching relay for said trunk circuit, means for applying ringing current to the end of the trunk circuit to which is connected said link circuit, said ringing current being of 40 a frequency not to affect the high frequency relay associated with that end of the trunk circuit but causing the operation of the alternating current relay of that end to effect the operation of one of said switching 45 relays, thereby connecting the high frequency generator with the trunk circuit and causing the operation of the high frequency relay at the opposite end of the trunk circuit, the operation of the high frequency relay at the distant end of the cord circuit causing the operation of said second switching relay to connect said first generator with 50 said trunk circuit to actuate the central office signal at the distant end of the cord circuit, notifying the operator that a connection is desired, a second link circuit for connecting said trunk circuit to said called subscriber's line, and telegraphic instruments connected to each conductor of said 55 trunk circuit, said telegraphic and telephonic instrumentalities being so connected and operable as not to interfere with the correct operation of each other.

55 60 65 70 75 80 85 90 95 100 105 110 115 120

eration of said second switching relay to connect said first means in circuit with said signal to effect actuation of said signal at 65 said other exchange thereby notifying the operator that a connection is desired, and a second link circuit at said other exchange for connecting said trunk circuit to said called subscriber's line.

11. A system of the character described including a calling subscriber's line and a called subscriber's line, a trunk circuit terminating at its ends in two different exchanges, a link circuit for connecting said calling subscriber's line to said trunk circuit at one of said exchanges; a central office signal connected to said trunk circuit at the other of said exchanges, a generator for operating said signal, an alternating 80 current relay, a high frequency relay, a high frequency generator and a switching relay operatively associated with each end of said trunk circuit; the high frequency generator at one end of said trunk circuit adapted to operate the high frequency relay at the other end of said trunk circuit via said trunk circuit, and the switching relay at said one end adapted to connect the high frequency generator to the trunk circuit, ringing current means, a second switching relay for said trunk circuit, means for applying ringing current to the end of the trunk circuit to which is connected said link circuit, said ringing current being of 85 a frequency not to affect the high frequency relay associated with that end of the trunk circuit but causing the operation of the alternating current relay of that end to effect the operation of one of said switching relays, thereby connecting the high frequency generator with the trunk circuit and causing the operation of the high frequency relay at the opposite end of the trunk circuit, the operation of the high frequency relay at the distant end of the cord circuit causing the operation of said second switching relay to connect said first generator with said trunk circuit to actuate the central office signal at the distant end of the cord circuit, notifying the operator that a connection is desired, a second link circuit for connecting said trunk circuit to said called subscriber's line, and telegraphic instruments connected to each conductor of said trunk circuit, said telegraphic and telephonic instrumentalities being so connected and operable as not to interfere with the correct operation of each other.

Signed by me at Chicago, in the county of Cook and State of Illinois, this 19th day of May, 1919.

ORMOND F. CASSADAY.
